APPARATUS FOR MAKING RAYON CAKES

Harry Rubinstei, Brooklyn, N. Y.

Application July 1, 1942, Serial No. 449,338

2 Claims. (Cl. 57—76)

This invention relates to methods and apparatus for the manufacture of rayon yarn, with particular reference to that step thereof that relates to the treatment of the so-called rayon cake.

One object of the invention is to provide for the improved making of a rayon cake so as to avoid the wear or fuzziness on the outer portion of the cake, which represents rayon strand that must be discarded because it has been damaged.

Another object of the invention is to provide for the improved winding of a cake so that it may be washed and cleaned and then readily unwound without tangling or tearing.

A further object of the invention is to provide improved methods and apparatus whereby the hardened filament rayon strand can be centrifugally spun or coiled in a whirling bucket to form the cake which is subsequently washed and dried and then rewound to form cones, skeins and tubes as desired, the new and improved rayon cake being produced in a simple, inexpensive manner well adapted for quantity production without the resultant waste and loss of time in the manufacture of the yarn as heretofore encountered.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a schematic perspective isometric view with parts removed, showing an apparatus embodying the invention.

Fig. 2 is a sectional view on the line 2—2 of Fig. 1.

Fig. 3 is a view in elevation showing the liner removed and expanded to release for removal the rayon cake, a portion of which has been broken away.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different con-

structions. The accompanying drawing, therefore, is submitted merely as showing the preferred exemplification of the invention.

In the invention of the process, certain of the features disclosed may be replaced by other equivalent characteristics, and certain steps may be omitted, and the apparatus employed is to be regarded as offered in a suggestive rather than in a limiting sense.

- 16 Referring in detail to the drawing, 10 denotes an apparatus embodying the invention. The same is particularly adapted for the practise of the new method, which relates to the process of making rayon yarns according to which cellulose sheets are softened by sodium hydroxide, then shredded, treated with carbon bisulphide, then with dilute sodium hydroxide, ripened, filtered, and finally expressed through minute orifices to form filaments which are hardened in a solution to form a rayon strand from which the cake is made. In making this cake, a bucket was whirled at high speed to centrifugally lay the strand against the wall of the bucket, an axial reciprocating feeder in the bucket causing 20 the coiling or winding to proceed uniformly up and down to form the cake in the general shape of a tube. This cake was then washed and dried to eliminate the tackiness of the strand to form the finished yarn, and the cake was then rewound to produce articles sold to knitters and weavers.

- In accordance with the above described process, there was provided a chamber or container 11, usually called a box, pot or bucket, generally cylindrical but preferably somewhat concoidal for easier removal of the rayon cake. This bucket was removably supported on a device 12 coaxial therewith whereby the bucket was rotated or whirled at very high speed, and could be withdrawn from the device 12 for removal of the cake without stopping the operation of said device. The raw or tacky rayon strand 13 consisting of hardened rayon filaments was fed to the bucket by passing around a suitable rotary or pulley device 14, thence through feeder 15 comprising an eye 16 and a glass tube 17 coaxial with the bucket. This feeder was axially reciprocated at a relatively slow rate by suitable 40 means comprising an arm-like structure 18. Closing the top of the bucket was a removable cover 19 having a central opening 20 for passage of the feeder tube 17. In operation the cake was wound by throwing the rayon strand centrifugally against the wall 21 of the bucket 11, 45

the reciprocation of the feeder causing the strand to be laid relatively uniformly up and down.

Because the inside face of the wall 21 was very smooth, I perceived that slippage occurred which caused excessive wear and fuzziness of the outer portion of the rayon cake, so that in re-winding it was customary to discard between 100 and 200 yarns of each cake. A source of great trouble in the rewinding was that the yarn was often tangled and frequently broke. These difficulties caused tremendous loss, of material, time and labor, in this industry in which production is very great.

I perceived that the wear and fuzziness of the outer portion of the rayon cake could be avoided if sufficient frictional engagement were provided to avoid slippage as between the cake and the rotary wall. If only a small degree of friction were provided, the wear and fuzziness referred to would be aggravated, and this is the reason why the wall of the bucket has heretofore been polished or formed very smooth. But a relatively substantial frictional resistance, sufficient to avoid rotary slip, would produce a rayon cake whose outer portion can be used as effectively as any other part thereof. This frictional surface may even include definite projections or ridges of which a multiplicity may be provided spaced throughout the inner surface of the rotary container. Preferably such engaging elements should be so formed as to avoid cutting or damaging the rayon strand by reason of relatively sharp or thin edges. But otherwise they may be very small in height, or as much as one eighth of an inch high. They may be formed in some cases directly on the wall 21 of the bucket, but are preferably formed on a removable, desirably expandible liner 22 for the bucket, as herein-after described.

To avoid tangling of the rayon yarn upon un-winding the cake, this invention provides for a stratified winding of the strand 13 in making the rayon cake. The principle involved is that the yarn of one strata or portion shall not readily mix with or become entangled with that of another strata or portion. One example of such winding is the so-called "diamond-like reeling" which is well known for other products. But such reeling is not possible at the extreme speeds used in centrifugally winding rayon strands, say, between 7000 and 9000 r. p. m. To accomplish such reeling, the speed of reciprocation of the strand feeder 15 would have to be increased to a suitable relation to the rate of rotation of the bucket. Such a speed of reciprocation would be unduly high, because vibratory and other difficulties would be encountered, while the centrifugal winding of the rayon strand would become difficult and lead to breakage of the strand. I prefer to substantially increase the speed of reciprocation of the feeder 15 to a reasonable degree, for example, from 40 or 50 to 80 or 100 or more reciprocations per minute, and in conjunction with this change, I arrange the projections or ridges above referred to so as to produce horizontal stratification of the outer portion of the rayon cake. Preferably the projections or ridges at different elevations are horizontally offset so that the stratification of the strands in the cake shall be angular for better distribution of the weight of the yarn. This structure may be provided on the bucket but is preferably formed on the liner 22 for easy removal of the cake and disengagement thereof

from the projections. The details of the construction involved will now be described.

5 The liner 22 may be formed of metal or composition material and is shaped to accurately fit the inside of the bucket 11 so as to be non rotatably locked thereto. This may be effected by one or more keyways 23, each of which may include a groove 24 in the liner and a ridge 25 in the bucket 22. Thus the liner is readily engaged with the bucket upon insertion, and is disengaged upon removal from the bucket. In 10 general, the liner may accurately fit the bucket so as to be supported thereby against the centrifugal forces, especially if the liner is expansible. Thus when rotation of the bucket has stopped, the liner may contract for removal without binding in the bucket.

15 The liner 22 may have an annular bottom flange 26 to facilitate removal of the rayon cake therewith. It may also have an upper annular flange or lip such as 27 or other suitable means to facilitate the lifting out of the liner from the bucket. This flange may afford a stop to limit the insertion of the liner to prevent binding with a conoidal bucket. For expansibility, the liner may be split at one section so as to open up like a spring, or it may be diametrically split as shown at 28 so as to form relatively like sections 29 as indicated in Fig. 3. These sections are 20 adapted to fit together accurately without any seam or break, as if there were no split.

25 Formed on the inside face of the side wall of the liner 22 is a frictional gripping means for preventing relative slippage of the rayon cake or for causing a stratified winding of the rayon strand or for both purposes. Accordingly the frictional means may be designed to fulfill the desired objects. By way of example, a multiplicity of projections are provided; these may 30 result by forming generally annular ridges, each of which may form a ring or all of which may form a helix. Such ridges 30 preferably lie in planes at an angle to the bucket axis and they define therebetween grooves 31. These cooperate with the increased speed of reciprocation of the feeder 15 as hereinbefore described to produce a tubular or so-called rayon cake 32 as shown in Fig. 3 in which the turns of rayon of at least the outer portion of the cake are stratified, for 35 example, with respect to the axis of the same and in generally horizontal planes. These planes are at a small angle to the horizontal determined by the speed of reciprocation of the feeder, but this angle need not be shown herein, the fine line showing of Fig. 3 being sufficient. During the whirling of the bucket 11 and its liner 22, the rayon strand 13 is centrifugally thrown against the ridges 30 and into the grooves 31 as the strand tends to move outward as far as possible. 40 In consequence, the path of the strand is undulating, the undulations lying along a circle. Preferably the ridges 30 lie at an angle of approximately 30 to 45 degrees with the vertical to cause ample offset between the undulations of successive turns of strand.

45 If the projections 30 are used only to frictionally grip the rayon cake against slippage, the projections need not follow the pattern shown in Fig. 1 but may lie haphazard or in horizontal groups. But in either case, the sides of the projections should be beveled or curved so as to avoid edges which might injure or break the delicate rayon strands or cause them to catch and mar the uniformity of the reeling.

50 In describing the apparatus, the process in-

volved has been fully discussed. When the rayon cake 28 has been completed, the bucket 11 is removed and the liner 22 withdrawn, expanded at its split 23, and the cake removed without interference by the projections. The cake may then be washed and dried, and finally rewound in the form of cones, tubes, skeins, or other commercial articles. The waste of material, time and labor is avoided and the objects of the invention fulfilled.

The direction of winding of the rayon cake relative to the angle of the ridges 30 is preferably such that in unwinding the cake, the "approach" is at an obtuse angle to the topside of the ridges 33. In other words, the strand leaves each ridge at an acute angle. This may be readily observed in Fig. 3 in which the arrow 34 indicates the direction of movement of the strand in unwinding. This approach is favorable for reducing any tendency to tangling to the strands. The ridges 33 will appear in the outer portion of the rayon cake and will gradually become reduced and may finally almost disappear inward. But they will have a marked effect in eliminating entanglement and tearing of the yarns especially at the outer portion of the cake in which this difficulty has been most marked. And the substantial reduction of wearing of the outer portion of the cake will materially aid in realizing the advantage noted. The spacing between the ridges 30 is intended to be sufficient to produce the undulated winding and to cause different resistances to be exerted against the centrifugal force of the strand so that the stratified reeling shall be effective for its intended purposes. Thus the resistance at the grooves

will be less and cause less tension than at the ridges 30.

I claim:

1. In an apparatus for making a cake of a hardened rayon strand for subsequent washing and drying and unwinding of the cake, a whirling bucket, and a removable, expansible liner therein, said liner having means for frictionally gripping the cake to prevent rotary slippage thereof and deterioration of the outer portion of the cake, said liner being engaged and whirled by the bucket and being expansible after removal from the bucket for removal from the cake.
2. In an apparatus for the manufacture of rayon yarn from filament extended hardened strands coiled into cake form for subsequent washing, drying, and unwinding, the combination with a whirling bucket, reciprocable means for centrally feeding a strand to the bucket, actuator means for whirling the bucket at high speed and for causing reciprocation of said means at such a rate that the strand is centrifugally uniformly laid on the wall of the bucket, and control means on the inside of the bucket whirling therewith for upsetting the otherwise even path of winding of the strand to produce stratified reeling of the cake, a removable liner in the bucket engaged therewith so as to whirl with the bucket, said liner having said control means comprising generally annular projections arranged in parallel planes at an angle to the axis of the bucket, said liner being expansible upon removal from the bucket to disengage the projections from the cake.

HARRY RUBINSTEIN.
